UNITED STATES PATENT OFFICE.

REUBIN MILTON RETHERFORD, OF MUNCIE, INDIANA, ASSIGNOR TO RETHERFORD BROS. CO., OF MUNCIE, INDIANA, A CORPORATION.

DESIGN FOR A CHANDELIER-BODY.

48,607.

Specification for Design.

Patented Feb. 22, 1916.

Application filed February 23, 1915. Serial No. 10,150. Term of patent 3½ years.

To all whom it may concern:

Be it known that I, REUBIN MILTON RETHERFORD, a citizen of the United States, residing in Muncie, in the county of Delaware and the State of Indiana, have invented a new and original and ornamental Design for Chandelier-Bodies, the same being illustrated in the accompanying drawing, showing a perspective view of my new design.

I claim:

The ornamental design for a chandelier body, as shown.

R. MILTON RETHERFORD.

Witnesses:

THOMAS L. RYAN,
EDWARD M. HIGHLANDS.
